CLAIM

The ornamental design for a bus panel add-on kit, as shown and described.

DESCRIPTION

FIG. 1 is a rear view of a bus panel add-on kit showing my new design, in relation to a bus shown in phantom lines;

FIG. 2 is a top view thereof;

FIG. 3 is a bottom view thereof;

FIG. 4 is a side view thereof, the opposing side view being substantially identical; and,

FIG. 5 is a front view thereof.
